SOCIETE ANONYME ETABLISSEMENTS ED. JAEGER, OF LEVALLOIS-PERRET, SEINE,
FRANCE

CATCH HINGE

Application filed February 4, 1931, Serial No. 513,406, and in France March 21, 1930.

This invention has for main object to provide a bolt hinge which is applicable in any case required to connect two elements having relative angular movements, and allows at will, either to hold these two elements completely stationary, or to permit them to move about the axis of their common connection.

Such a hinge is conveniently applicable to articles of jewelry for which the external appearance has quite a special importance. The hinge forming the subject-matter of the invention does not differentiate by its aspect from an ordinary hinge, but it ensures absolute security, as accidental unlocking is rendered practically impossible.

These advantages or commercial results being borne in mind, the bolt hinge according to the invention is mainly characterized in that the axis connecting the hinge eyes is divided into distinct elements each angularly and respectively connected to one of the elements of the hinge and axially movable relatively to each other, so that they can occupy two extreme positions: one in which they are angularly connected and thereby ensure the locking of all the hinge eyes, and the other in which they are not angularly connected for allowing the free operation of the elements connected by the hinge.

Such as defined in its principle, the invention can be carried out according to various forms of construction which can differ from each other particularly:

(a) By the nature of the means ensuring the angular connection between the elements of the axis of the hinge eyes. In a simple form of construction, the connection is obtained by means of diametral tenons and mortices provided in the adjacent ends of two

elements the axes of which are close together.

(b) By the mode of acting on the elements of the axis for imparting thereto the required axial displacements. Concerning this point, the invention specifically relates to an arrangement in which the elements of the

axes are restored to locking position by a spring, the compression of which for effecting unlocking, is effected by acting on a knob or on two knobs accessible at the ends of the hinge.

(c) By the fact that the unlocking action can be exerted on only one of the elements of the axis, or by the fact that it must be simultaneously exerted on these elements for effecting the unlocking operation. In this last form of construction, which seems to be the most advantageous, a double security is obtained against accidental unlocking.

The invention also relates to the application of the bolt hinge as defined in the foregoing, to jewels of the "buckle" type comprising two small plates hingedly connected and devised for clamping the fabric of clothes and securing thereto the end of a chain or of a ribbon to which is attached a watch or other jewel.

The invention further relates particularly to new commercial products constituted by watches on the case of which are provided hinge eyes connected, by a bolt hinge in accordance with the main object of the invention, to the hinge eyes of a clip member, in order to allow of securing the watch on any part of the clothes.

A form of construction of a bolt hinge is mainly characterized in that the locking devices are directly controlled by the hinge eyes which are to be acted upon, in the direction of the angular displacements, by action on the elements rigid with these hinge eyes, by exerting on these elements, a stress greater than that considered sufficient for ensuring security.

A form of construction of an improved hinge according to the invention is characterized in that one of the hinge eyes is rendered rigid, at least angularly, with a resilient locking bolt, or subjected to the action of resilient members, this locking bolt

being combined with a housing or a staple rigid with the other hinge eye.

Another form of construction, subsequently described by way of example only, is mainly characterized in that use is made, as resilient locking device for two hinge eyes on the one hand, of a bevelled locking bolt rendered rigid, only angularly, with one of the hinge eyes, this locking bolt, which can move in translation, being subjected, in one direction, to the action of a spring and, on the other hand, of a staple rigid with the other hinge eye, this staple being provided with a slot (preferably a diametral slot) having a cross section corresponding to the V-shaped bevelled portion of the locking bolt, so that any displacement of the hinge eyes, from the locking position, can be effected only by exerting a sufficient stress function of the characteristics of the spring and allowing to relatively move the inclines of the staples and of the locking bolt.

The accompanying drawings illustrate, by way of example only, several forms of construction of bolt hinges according to the invention.

Figs. 1 and 2 are two axial sections of a first form of construction of a bolt hinge.

Figs. 3 and 4 on the one hand, and Figs. 5 and 6 on the other hand, are two views similar to Figs. 1 and 2, of a second and third form of construction.

Figs. 7 and 8 are an elevation and a plan view of a "buckle" constituting one of the applications of the invention.

Fig. 9 is a perspective view of a watch such as above defined.

Fig. 10 is a perspective view of a clip or buckle according to the invention allowing to attach a watch on clothes.

Fig. 11 is an axial section of a fourth form of construction, the clip being closed or entirely open.

Fig. 12 is a corresponding view, the clip being in the course of opening, that is to say unlocked.

In the example of construction of Figs. 1 and 2, two sets of hinge eyes are mounted on one and the same axis made of two elements 1 and 2. The hinge eyes 3^a, 4^a and 5^a belong to one of the elements connected by the hinge; the hinge eyes 6^b and 7^b belong to the other element.

The element 2 of the axis is permanently secured on the hinge eye 5^a by means of a diametral screw 8, whilst the element 1 of the same axis is angularly connected to the hinge eye 6^b by the engagement of a radial finger 9 in a longitudinal slot 10 of the hinge eye 6^b.

A spring 11, interposed between the element 1 and the bottom of the hinge eye 3^a, returns towards each other the two opposite ends of the elements 1 and 2 of the axis.

These two ends are respectively provided

with a diametral tenon 14 and with a mortice 15 which are in engagement for a relative angular position of both sets of hinge eyes (locking position). It is in fact impossible to move the two parts connected by the hinge when the two elements 1 and 2 of the axis are in engagement as shown in Fig. 1.

For unlocking, it suffices to pull outwardly a knob 12 connected, by a rod 13, to the element 1 for compressing the spring 11 and releasing the tenon 14 from the mortice 15. Both sets of hinge eyes are free to move and can assume for instance the relative positions they occupy in Fig. 2.

The example of Figs. 3 and 4 differs from the preceding one only in that the pull knob 12 of Figs. 1 and 2 is replaced by a push-button 12^a, the rod 13^a of which passes through an axial bore of the element 2 and is secured by screwing on the element 1. The spring 11 bears upon a bottom 11^a secured to the hinge eye by any suitable means. The same reference numbers designate like parts or parts which correspond to each other in Figs. 1 to 4. In Fig. 4, the hinge eyes, 6^b and 7^b have moved to the extent of 90 degrees relatively to the position they occupy in Fig. 3.

In the example of construction of Figs. 5 and 6, unlocking takes place by moving by pressure both knobs 12^a and 12^b towards each other. The knob 12^a freely passes through the element of the axis and is secured by screwing on a slide-block 1^a guided in a bore 1^b of the element 1 of the axis. A diametral finger of the slide-block 1^a passes through two longitudinal slots 1^d and 10 respectively belonging to the element 1 of the axis and to the hinge eye 6^b. A radial finger 16 of the element 2 is guided in a longitudinal slot 10 of the hinge eye 4^a. It will be seen that the set of hinge eyes 3^a, 4^a, 5^a is angularly rigid with the element 2 of the axis, whilst the set 6^b and 7^b is rigid with the element 1. Two radial tenons 14 provided on the slide-block 1^a ensure locking when they extend into corresponding mortices 15 of the element 2. A spring 11 acts for constantly returning towards each other the opposite ends of the elements 1 and 2 and of the slide-block 1^a.

The operation is as follows:

Fig. 1 shows the locking position. If the fingers are used for moving both knobs 12^a and 12^b towards each other by compressing the spring 11, the elements 1 and 2 and the slide-block 1^a are brought in the positions they occupy in Fig. 7, the tenons 14 are released from the mortices 15, and the locking is obtained.

The passage from the locking to the unlocking positions can be examined according to two successive conditions:

(1) By acting on the knob 12^a, the elements 1 and 2 remain stationary, the slide-block 1^a

is moved towards the left according to a distance

$$\frac{d}{2},$$

5

d being the depth of engagement of the tenons 14 into the mortices 15.

(2) By acting on the knob 12^b, whilst the knob 12^a and the slide-block 1^a are held stationary both elements 1 and 2 move towards the right according to a distance

$$\frac{d}{2},$$

15 this completing the disengagement of the tenons 14 from the mortices 15.

The application of the invention to jewels of the "buckle" type is shown in Figs. 7 and 8. The jewel or "buckle" comprises two small plates 17 and 18 connected by a hinge such, for instance, as that shown in Figs. 5 and 6. The plate 17 is provided on its inner face with points 19 the ends of which, in closing position, can enter perforations on the plate 18. When both plates are moved towards each other by clamping between them the fabric of a garment (lapel of a coat for instance) and the end of a ribbon or of a chain as explained above, the hinge is locked, 30 it can be unlocked only by simultaneously pressing on the knobs 12^a and 12^b.

Fig. 9 illustrates a watch on the case of which are secured hinge eyes connected by a bolt hinge, constructed for instance as shown in Figs. 5 and 6, to a small plate 20 capable of receiving any desired decoration. This plate 20 provided with points such as the points 19 of Figs. 7 and 8, allows of securing the watch in a coat pocket, or on the 40 wrist band of a sleeve. Thus secured, the watch cannot accidentally unfasten itself.

The buckle illustrated in Figs. 10, 11 and 12 comprises two groups of hinge eyes mounted on one and the same axis composed of two 45 elements 1 and 2. The hinge eyes 17^a and 17^b belong to the jaw 17 of the clip, and the hinge eye 18^a is rigid with the jaw 18.

The hinge eye 17^a is permanently secured by a diametral screw 9 on the said element 2, whilst the hinge eye 18^a is rendered rigid by a screw 16, with the element 1. The latter is loosely mounted in the hinge eyes 17^a and 17^b and occupies only a portion of the width of the hinge eye 17^a for allowing the element 2 to take a bearing thereon.

The element 1 is angularly connected, in locking position, to the element 2 forming a kerf at 23, by a locking bolt 22 extending in the kerf 23.

60 The bevelled locking bolt 22 has a rectangular cross-section. It slides in a corresponding diametral recess 22^a of the element 1 and is terminated by a spindle 24 moving in an axial recess 24^a of the same element 65 1. This spindle 24 extends in a recess 25

of larger diameter in which a returning spring 26 is arranged. This spring bears, on the one hand, with interposition of a steel washer or the like, on the end wall of the hinge eye 17^b which forms a cap and, on the 70 other hand, on the spindle 24 of the locking bolt 22 through the medium of a washer 27.

The kerf 23, corresponding to the bevelled end of the locking bolt 22, forms inclines, so that when the locking bolt is angularly driven by the user acting on the jaws of the clip, it moves angularly and in translation for coming to the position shown in Fig. 12. An end piece or member 28, preferably of precious metal as the hinge eyes and jaws, is provided 80 with a spindle 28^a entering an axial bore 29 of the element 2. The latter can conveniently be made of a hard metal such as steel, for avoiding the distortion of the locking bolt 22 or of the inclines of the kerf 23. The diametral screw 8 for securing the element 2 to the hinge eye 17^a, passes through the spindle 28^a of its end member 28, thus rendering it 85 rigid with the whole.

The operation of the locking device illustrated in Figs. 10, 11 and 12 is as follows:

The clip or hinge being closed and locked, it is necessary for opening it to exert a sufficient stress on the jaws for overcoming the reaction of the spring 26. The action of the 95 inclines of the kerf 23 on the bevelled portions of the locking bolt 22, causes an axial translation of the latter which, angularly connected to the jaw 17, is angularly driven with the latter. After a sufficient angular displacement, its end rests on the plane end portions of the element 2. When the clip is opened through an angle of 180°, the locking bolt 22 again enters the kerf 23 and locks the clip in the open position.

As in the forms of construction illustrated in Figs. 1 to 9, one of the jaws or both are provided, on their inner face, with points 19 the ends of which, in closed position, can enter perforations of the opposite small plate or 100 jaw.

What I claim as my invention and desire to secure by Letters Patent, is:

1. In a catch hinge, knuckles, a bolt of two 115 elements disposed in the interior of the knuckles, resilient means for supporting the two elements of the bolt against each other and means comprising two push-buttons for disengaging the bolt by simultaneously pressing the two push-buttons.

2. In a catch hinge, knuckles, a bolt of two elements disposed in the interior of the knuckles, resilient means for supporting the two elements of the bolt against each other and means comprising two push-buttons placed at the ends of the bolt for disengaging the bolt by simultaneously pressing the two push-buttons.

3. In a catch hinge, knuckles, one half of the bolt engaging in the knuckles for slid-

130

ing therein in translation, means for preventing the rotation of this half of the bolt relatively to one of the knuckles and for limiting its translation, a second half of the bolt engaging in the knuckles for sliding therein in translation, means for preventing the rotation of this second half of the bolt relatively to the other knuckle and for limiting its translation, a spring for supporting the two halves of the bolt against each other, means comprising two push-buttons for separating the two halves of the bolt, the necessary path to the unlocking position being greater than the possible translation of each of the halves of the bolt.

4. In a catch hinge, knuckles, one half of the bolt engaging in the knuckles for sliding therein in translation, a rod secured to this half of the bolt and extending through an elongated hole of one of the knuckles for preventing the rotation of this half of the bolt relatively to the said knuckle and for limiting its translation, a second half of the bolt engaging in the knuckles for sliding therein in translation, a rod secured to this second half of the bolt and extending through an elongated hole of one of the knuckles for preventing the rotation of this half of the bolt relatively to the said knuckle and for limiting its translation, a spring for supporting the two halves of the bolt against each other, means comprising two push-buttons for separating the two halves of the bolt, the necessary path to the unlocking position being greater than the possible translation of each of the halves of the bolt.

5. In a catch hinge, knuckles, an axis passing through the said knuckles comprising a tubular cylindrical element the inner face of which is mortised, a second tubular cylindrical element terminating externally in a first push-button, a rod adapted to slide in the interior of the first tubular cylindrical element which rod is provided internally with a part of larger diameter engaging in the second cylindrical element and possessing tenons for engaging in the mortices of the first tubular cylindrical element, this rod terminating externally in a second push-button, a spring interposed between the first cylindrical element and the second push-button, means for preventing the rotation and for limiting the translation of the first cylindrical element relatively to one of the knuckles and of the second cylindrical element relatively to the other knuckle, the limited translation of each of these elements being less than the necessary path to the unlocking position.

In testimony whereof I have signed this specification.

CHARLES HILAIRE HENRI RODANET.
